CLAIM

The ornamental design for an illuminated fiber housing assembly, as shown and described.

DESCRIPTION

FIG. 1 is a top perspective view of an illuminated fiber housing assembly showing our new design;

FIG. 2 is a left side view thereof;

FIG. 3 is a right side view thereof;

FIG. 4 is a top view thereof; and,

FIG. 5 is a bottom view thereof.

The radiating lines extending from the cylindrical shaped fiber element represent illumination of the fiber element. The broken lines depicting the remainder of the illuminated fiber housing assembly show features that form no part in the claimed design.
